UNITED STATES PATENT OFFICE.

EMIL A. STRAUSS, OF CHICAGO, ILLINOIS.

SAFE OR VAULT DOOR.

No. 901,047.

Specification of Letters Patent.

Patented Oct. 13, 1908.

Application filed October 13, 1905. Serial No. 282,614.

To all whom it may concern:

Be it known that I, EMIL A. STRAUSS, a citizen of the United States, of Chicago, in the county of Cook and State of Illinois, have invented certain new and useful Improvements in Safe or Vault Doors; and I do hereby declare that the following is a full, clear, and exact description thereof, reference being had to the accompanying drawings and to the letters of reference marked thereon, which form a part of this specification.

This invention relates to safe or vault doors and more especially to a door additional to the usual or main door of a safe or vault, commonly called an emergency door, the same being equipped with its own locking means separate from and independent of the locking means for the main door, and which is therefore, adapted to be opened to give access to the interior of the safe or vault in case the opening of the main door is prevented by failure of the locking devices of the said main door to operate or from some other cause.

The invention consists in the matters hereinafter described and pointed out in the appended claims.

In a safe or vault constructed in accordance with my invention, the main door, which may be equipped with any desired or preferred form of locking means, is provided in the body, or within the margins thereof with a doorway or opening for an emergency door and with an emergency door adapted to fill or close such doorway or opening, together with locking means for such emergency door, of any desired or preferred form, which locking means are separate and distinct from the locking means for the main door. In other words, the said main door and the emergency door, which latter is adapted to close an opening or doorway in the main door, are provided with separate and independent locking means adapted to be independently actuated, so that in case of failure from any cause of the locking devices of the main door to properly operate, the emergency door can be utilized as a means of gaining access to the safe or vault.

As a separate improvement my invention includes a main door of circular form, and a circular door occupying the central portion

of the area of the main door, said emergency door being provided with locking means independent of the bolts and bolt-work of the main door.

My invention also includes a main door of circular form provided with bolt-work embracing radial bolts occupying the marginal part of the door only and a circular emergency door located within the central part of the main door inside of the bolt-work thereof, together with other features and details of construction relating to said main and emergency doors, as hereinafter pointed out and specified in the appended claims.

The accompanying drawings illustrate one practical form in which my invention may be embodied, the door illustrated in said drawings being of circular form and having marginally arranged bolt-work and a circular, centrally arranged, emergency door located within and carried by said main door.

As shown in the drawings:—Figure 1 is a face view of a safe equipped with a main door and an emergency door embodying my invention. Fig. 2 is an inside face view of the main door and emergency doors. Fig. 3 is a sectional view of the main and emergency doors, together with the adjacent parts of the jamb or wall of the safe or vault that surrounds the main door, said section being taken on line 3—3 of Fig. 2. Fig. 4 is a detail view of the actuating devices for the radially arranged bolts of the emergency door.

As shown in said drawings, A indicates the wall of a safe or vault, in which is formed an opening or doorway, and B the main door which fits within and closes said opening or doorway in the usual or any preferred manner.

C indicates an auxiliary or emergency door which fits within and serves to close the emergency opening or doorway formed within the main door B.

D is a hinge member by which the main door B is movably supported on the safe or vault, so that it may be swung into and out of its position within the main doorway or opening. Said hinge member D has upper and lower, horizontal, outwardly extending arms d d¹ which are connected by vertical pivots with lugs D¹ D² attached to the wall

A of the said safe or vault at one side of the door, and is also provided with upper and lower horizontal arms d^2 d^3 which are connected by vertical pivots with lugs D^3 D^4 attached to the door B near the top and bottom thereof.

In the form of my invention illustrated in the accompanying drawings, the emergency door is supported on the main door B. In 10 said drawings E indicates a hinge member or crane hinge for supporting the emergency door C upon the main door B. Said hinge member E has horizontal, outwardly extending, upper and lower arms e e^1 which are 15 pivotally connected by vertical pivots with lugs E^1 E^2 attached to the main door B at one side of the emergency door. The hinge member E is also provided with inwardly extending, horizontal, upper and lower arms 20 e^2 e^3 which are connected by vertical pivots with lugs E^3 E^4 attached to the emergency door C near the top and bottom thereof.

In order to provide for the necessary swinging movement of the hinge members 25 D and E without interference with each other, a construction is provided as follows: The main or upright portion of the hinge member D is located at such distance laterally from the pivotal axis of the hinged connection between the said hinge member and the main door as to permit the hinge member E to swing outwardly at right angles or nearly so to the face of the main door; the inner margin of said main part of the hinge 30 member D for this purpose being located at a greater distance from the pivots connecting the arms e^2 e^3 with the emergency door, than from the pivots connecting the hinge member E and the main door B, the result 35 of this arrangement of the parts being that the hinge member E may be swung outwardly, in opening the emergency door, far enough to permit the said door to be fully opened before the said hinge member E 40 comes in contact with the said inner margin of the upright part of the hinge member D. The inner arms d^2 d^3 of said hinge member D are, moreover, vertically separated by a space greater than the height of the hinge 45 member E and the emergency door C, so that the said door and the part of the hinge member E adjacent thereto may be swung outwardly into the said space between said arms d^2 d^3 .

50 The main door B is shown as provided with a common form of pressure devices or means for forcing the door tightly into place within the door jamb, the same as illustrated consisting of two horizontal parallel rock shafts or "pressure bars" F F having eccentrically arranged projections at their ends adapted to engage holding members F^1 F^1 on the safe or vault wall, together with actuating means for said rock shafts, embracing 55 an upright actuating shaft F^2 having opera-

tive connection with the rock shafts F F by means of beveled gears f f^1 , and a rotative hand wheel F^3 having geared connection of any suitable character with the shaft F^2 , for turning the latter.

The emergency door E is shown as provided with a like device for forcing it against its seat, the same consisting of a horizontal rock shaft or "pressure bar" G mounted on the outer face of the door and having at its ends projections which engage locking members G^1 G^1 on the main door B, together with a hand wheel G^2 having geared connection of any suitable character with said rock shaft G for turning the same. The pressure devices for both the main and emergency doors operate to maintain the doors in parallel relation with the door openings or jambs in which they fit, as said doors are moved inwardly and outwardly, thereby assuring the proper seating of the doors against the bearing or contact surfaces of the jambs.

The bolt-work illustrated in connection with the main door is similar to that shown and described in my Letters Patent No. 827,999, issued August 7th, 1906. Said bolt-work embraces two bearing rings H H¹ attached to the inner face of the door concentrically with each other, one ring being near the outer margin of the door and the other a short distance inside of said margin, and a plurality of radially arranged, cylindrical bolts I I I which fit and slide endwise in bearing apertures formed in said bearing rings.

J indicates a bolt actuating ring which is located between the outer and inner bearing rings H H¹ and extends between the several bolts and the face of the door. Said actuating ring is provided with a plurality of gear segments J¹ J¹ that extend from the side face of the ring into the spaces between the bolts. Each of the bolts is provided with lateral gear teeth located between the ends of the same and in the space between the two bearing rings H H¹.

K K indicate gear pinions which turn on axes perpendicular to the safe door and are located between the bearing rings H H¹ in the spaces between the bolts; said gear pinions intermeshing with the lateral gear teeth on the bolts and also with the gear segments J¹ J¹. Said gear pinions serve to transmit motion from the actuating ring J to the several bolts, so that by the turning of the ring simultaneous and equal movement is given to all of the bolts for casting and retracting the same. The gear pinions K are mounted on studs k k which are rigidly affixed to the door and project inwardly from the inner face thereof.

L indicates an actuating spindle which extends through the door and by means of which motion is given to the bolt-work from

the exterior of the door in casting and retracting the bolts. Said spindle L is provided outside of the door with a lever or handle L² (Fig. 1), and on the inner face 5 of the door with a gear pinion L¹ which intermeshes with one of the gear pinions K. When the spindle L is turned said pinion L¹ transmits rotary motion to the gear pinion engaged therewith and from the latter to the 10 actuating ring J.

M indicates a dogging bolt which is arranged radially and slides in a groove in the inner face of the safe door. The outer end of said dogging bolt is adapted to engage a 15 notch in the inner margin of the actuating ring J. The inner end of said dogging bolt is connected with a yoke-piece n at a point between the ends thereof; and the ends of said yoke-piece are connected with the ends 20 of the endwise movable members of two combination locks N N¹. N² N³, (Fig. 1), indicate the knobs of said combination locks, located on the outer face of the door. The actuation of either of said combination 25 locks results in the dogging bolt being drawn inwardly and released from engagement with the ring J.

O indicates a time lock which controls the movement of the dogging bolt.

30 Instead of the actuating spindle L described, the main door may be equipped with spring actuated automatic bolt actuating mechanism, controlled by a clock or timing mechanism, or an electrically operated means 35 may be employed for casting and retracting the bolts.

The locking mechanism for the inner or emergency door consists, as shown in the accompanying drawing, of bolt-work constructed substantially like that shown and described in my Letters Patent No. 859,531, issued July 9th, 1907.

40 As clearly seen in Figs. 2 and 4, P indicates a bearing ring attached to the door adjacent to the margin thereof and Q Q a plurality of radial bolts arranged to slide endwise in said bearing ring.

Q¹ Q¹ indicate radial, endwise movable rack bars, which are severally attached at 50 their outer ends to the bolts Q Q and arranged in offset relation to said bolts.

R indicates a central supporting plate which covers the inner ends of the several rack bars, and S is a centrally arranged 55 pivot stud on which is mounted a rotative gear pinion S¹. Said gear pinion is located between the plate R and the inner face of the door and the racks Q¹ Q¹ intermesh with the gear pinion S¹ and are arranged relatively to the pinion in opposite pairs. The 60 rack bars belonging to alternate bolts are, moreover, arranged in different planes so that the two sets of rack bars are in overlapping relation, as clearly seen in Fig. 4. 65 In the construction shown in the drawings,

eight bolts Q are employed, so that four of the rack bars are arranged in one plane and the four rack bars belonging to the alternate or intermediate bolts are in another plane; the result of this arrangement being that the 70 eight rack bars may be engaged with the pinion in the manner clearly shown in Fig. 4.

From the construction above described it will be manifest that the rotative actuating pinion S¹ has geared connection with all of 75 the bolts Q and that rotation of said pinion in one direction or the other will give simultaneous and equal movement to all of said bolts.

Casting and retracting movement may be given to the bolt-work described 80 through the medium of an operating spindle T which extends through the door to the outside of the same. Said spindle is shown as having on its inner end a pinion T¹ which intermeshes with gear teeth on the side of

one of the bolts Q. T², Fig. 1, indicates a hand lever on the outer end of the spindle T, by means of which the same may be actuated to throw the bolts. Instead of employing 85 an operating spindle such as described, casting and retracting movement may be given to the bolts through the use of a spring actuated, automatic bolt actuating device located on the inner faces of the door and controlled by a clock or timing 90 mechanism, or by electrically actuated means, as is heretofore common. I have, however, shown in the drawings, as a means for controlling the bolt-work, two combination locks

95 V V¹ which are mounted on the plate R and the moving parts of which are connected with the ends of a bar or yoke u. The central part of said bar u is connected by a link v with the laterally extending arm v¹ of a dogging lever V, the free end of which 100 is adapted for engagement with a lug or stud q on one of the bolts Q. The operating knobs of the combination locks V and V¹ on the outside of the door are indicated by V² 105 V³ in Fig. 1.

110 W indicates a time lock which is also mounted on the supporting plate R. Said time lock may be employed to dog the bolts Q and thereby prevent the withdrawal thereof until the time set for the safe to be opened, as is determined by the operation

115 of the time lock. Said time lock W is shown as provided with a dogging bar w, arranged to slide endwise in the casing of the time lock, and the outer end of which, when the 120 bar is extended, stands in the path of a lug q on one of the bolts Q, so as to prevent inward movement of said bolt. Said dogging bar will be controlled by the time lock

125 in the usual manner, the same being advanced to and held in its dogging position when the time lock is set for operation, and released and allowed to slide inwardly at a time determined by the running of the turning mechanism of the time-lock.

It is to be understood that the combination locks and time locks, shown as applied for the purpose of controlling the bolt-work of the main and emergency doors, are illustrated in the accompanying drawings, merely for the purpose of indicating one practical embodiment of my invention and that, so far as the essential features of my invention are concerned, any suitable or desired form 10 of electric or spring operated bolt actuating mechanism may be used both for the main and emergency doors.

The employment of an emergency door of size to permit access to the safe or vault located within or carried by the main door of the said safe or vault and provided with locking means operable independently of the locking means of the main door in accordance with my invention has a number of advantages as compared with an emergency door located in the walls of a vault or safe separate from said main door, some of which may be stated as follows: The cost of constructing the walls of a vault or safe provided with two doors, viz; a main door and an emergency door is very much greater than when the safe or vault is provided with one opening, viz; that for the main door only. Moreover, the opening for the auxiliary door 20 may be much more easily and cheaply constructed in the main door than in the wall of the safe or vault itself. Furthermore, it is frequently found difficult to provide a place for locating, in the walls of a vault or safe, an auxiliary or emergency as well as a main door, without the sacrifice of space within the building in which the safe or vault is located that would be available for other purposes.

40 An important advantage is gained by making the main and emergency doors of circular form, for the reason that the outer marginal surface of the main and emergency doors, as well as the inner marginal surface 45 of the main door, which forms the jamb for the emergency door, may be given accurate form by a grinding or like process, much more readily and economically when said marginal surfaces are circular than when 50 of other shape.

While I have shown the bolt-work of my earlier application in the accompanying drawings for the purpose of exemplifying my present invention, yet it is to be understood that I do not wish to limit myself to any particular form or construction of or in the locking means employed in connection with the main or emergency door, and that said locking means may include

either bolt-work or any other means for securing the doors in closed position, and that the actuating means for operating the locking means may either embrace parts extending through the doors, as in the case of combination locks, or may be without such parts, as in the case of spring actuated, or automatic bolt actuating mechanisms, or electric bolt actuating devices.

It is to be further understood that I do not desire to limit my invention to any of the features or details of construction described and illustrated in the accompanying drawings, except so far as the same are specified in the appended claims.

I claim as my invention:—

1. The combination with a main safe or vault door provided with an opening in its central part, and locking means therefor embracing bolts, means for casting and retracting the bolts and bolt dogging means, all of said locking means being located upon the marginal part of said door exterior of the said opening, of an emergency door adapted to fit within but which is removable from said opening, and locking means for said emergency door embracing bolts, means for casting and retracting the bolts and bolt dogging means, said locking means being mounted upon said emergency door and being operable independently of the operation of the locking means belonging to the main door.

2. The combination with a main safe door of circular form provided with a central, circular opening therein and locking means embracing radially arranged bolts, means for casting and retracting the bolts and bolt dogging means, all located within the annular space between the said central opening and the edge of the main door, of a circular emergency door adapted to fit within and removable from said opening, and locking means for said emergency door embracing locking bolts, means for casting and retracting the bolts, and bolt dogging means, said locking means being mounted on said emergency door and operable independently of the operation of the locking means belonging to the main door.

In testimony, that I claim the foregoing as my invention I affix my signature in presence of two witnesses, this 9th day of October A. D. 1905.

EMIL A. STRAUSS.
